UNITED STATES PATENT OFFICE.

WILLIAM F. HENDRY, OF OSSINING, NEW YORK, ASSIGNOR TO MANHATTAN ELECTRICAL SUPPLY COMPANY, INCORPORATED, OF NEW YORK, N. Y., A CORPORATION OF MASSACHUSETTS.

DRY CELL.

Application filed December 27, 1923. Serial No. 682,930.

To all whom it may concern:

Be it known that I, WILLIAM F. HENDRY, a citizen of the United States, residing at Ossining, in the county of Westchester and State of New York, United States of America, having invented certain new and useful Improvements in Dry Cells (Case #8), do hereby declare that the following is a full, clear, and exact description of the same.

10 This invention relates to dry cells and more particularly to an improved dry cell structure for facilitating the distribution of liquid therethrough.

It is the object of the present invention 15 to increase the efficiency of a dry cell by decreasing its internal resistance and also by providing means for freer circulation of gas generated by the reactions taking place in the cell.

20 In accordance with the main feature of the present invention, grooves are provided around the depolarizing mix surrounding a centrally located carbon electrode for affording passage of liquid around the mass 25 of depolarizing mix and to the bibulous container surrounding the latter and separating it from the zinc electrode, and also free circulation of gas.

The invention will be more clearly understood from the following detailed description of a preferred embodiment thereof.

In the drawings, Fig. 1 is a vertical cross-section of a portion of a dry cell embodying various features of the present invention, 35 and Fig. 2 is a plan view of a washer or tablet, a plurality of which serve to make up a cell.

40 Referring now to Fig. 1, 1 is a zinc container electrode, 2 a paper or other bibulous or cellulose lining inside of this electrode, 3 are tablets or washers compacted of a suitable depolarizing mixture, 4 is a carbon electrode projecting through the tablets 3. Each tablet 3 (Fig. 2) is provided with 45 grooves 5 radiating from the center towards its periphery. These grooves are preferably continued down the sides of the tablets as indicated at 6. Furthermore, the outside periphery of each washer 3 is bevelled, whereby when two washers are laid one 50 on top of the other, the bevelled surfaces will form a triangular trough 7 all around the tablets and therefore the depolarizing mix.

Water introduced into the structure will 55 pass through the radial passageways or grooves 5 and around the annular passageways or grooves 7, whereby the depolarizing mixture will be thoroughly soaked and the cellulose container 2 will also be properly 60 humidified.

Usually, in the operation of dry cells, a thin outer layer of the depolarizing mixture loses its porosity, becoming relatively 65 dry and impervious, which condition seriously interferes with the proper functioning of the cell, due to the difficulty of circulation of gas and moisture to facilitate electrolytic conduction and necessary chemical reactions.

70 I am aware that this impervious layer is attributed to various causes such, for example, as the formation of insoluble double salts of zinc and ammonium, and numerous 75 remedies have been proposed to dissolve, neutralize or counteract the formation of such salts. It is not at this time necessary to consider the causes of the phenomenon, but merely to point out that whatever the cause, my proposed improvement provides means 80 whereby the gas and moisture can escape from the body of the mix into the radial grooves, through them to the circumferential grooves and thus reach the active zone 85 much more readily than in any previous construction of dry cell.

In order thoroughly to moisten the paper lining, it was the practice first to moisten the paper provided within the zinc can and then to introduce the mass of depolarizing 90 mixture. The moistened paper tore easily during successive handling and this caused a relatively high percentage of damaged batteries. The provision of the troughs 7 and also grooves 6 eliminates the necessity 95 of first humidifying the paper 2. Liquid (with or without suitable chemicals) may be poured in the cell after the tablets 3 and the carbon 1 are in place, and the grooves 5, 6 and 7 will insure the proper distribution 100 of the liquid throughout the cell.

105 The invention is in many respects an improvement on the structure disclosed in my copending application Serial No. 673,538, filed November 8, 1923, and the annularly grooved tablets disclosed herein may be used in the combinations illustrated in my said application. It will be obvious to those

skilled in the art that the number and direction of the corrugations 5 may be varied, that the corrugations 6 may be eliminated to decrease the cost of manufacturing and 5 that the invention is not necessarily limited to dry cells composed of washers or tablets like 3.

What I claim is:

1. In a dry cell, two electrodes, depolarizing mix between said electrodes, passageways through said mix, and circular passageways around said mix into which said first mentioned passageways open.
- 10 2. In a dry cell, two electrodes, tablets compacted of depolarizing mix separating said electrodes, grooves in the upper and lower faces of said tablets, and grooves around said tablets.
- 15 3. In a dry cell, a container electrode, a second electrode centrally located therein, a

plurality of tablets compacted of depolarizing mixture surrounding said second electrode, a cellulose layer separating said tablets from said container electrode, annular grooves around said tablets constituted by bevelled edges of adjacent tablets, and grooves in the upper and lower faces of said tablets radiating towards said annular grooves.

25 4. In a dry cell, a zinc container electrode, a carbon electrode within said zinc electrode, depolarizing mix surrounding said carbon electrode, a lining of paper separating said mix from the zinc electrode, grooves around said mix, and passageways radiating through 30 said mix leading towards and opening into said grooves.

In witness whereof, I hereunto subscribe my name this 18th day of December, 1923.

WILLIAM F. HENDRY.
